RAILWAY SWITCH LOCK CONTROL SYSTEM

George J. Johaneck, Rochester, N. Y., assignor to General Railway Signal Company, Rochester, N. Y.

Application November 12, 1952, Serial No. 320,066

3 Claims. (Cl. 246—146)

This invention relates to systems for safeguarding railway traffic where hand operated track switches are located along the main tracks of railroads, and it more particularly pertains to an improved system of signal control wherein electric locks for hand operated track switches are involved.

Many railroads have electric lock protected hand operated track switches in their main line tracks for connecting with storage and industrial tracks, passing sidings, and the like. The release of the electric locks is commonly provided by joint action on the part of a traffic control operator at a remote point, and a trainman operating a manual control lever on the electric lock. As a safeguard for main line traffic when a train is to move off of a spur track onto the main, it is provided that signals governing traffic through the track switch on the main track are put to stop upon the initiation of operation of the switch lock. Conventional practice is to put such signals to stop, either upon the opening of the door of the switch lock mechanism, or upon initially moving the manual control lever of the switch lock mechanism for the release of the lock. It is also generally provided, after release of a switch lock, that a check be made of restoration of the lock to its full normal position, with the door closed, before a main line signal can again be cleared. These two requisites are met conventionally by including normal contacts of the lock mechanism circuit controller, and the door contacts of the mechanism, in the energizing circuit for the switch repeater relay of the associated switch.

Under the above described signal control system, there is the possibility that a trainman may attempt to operate the lock without the cooperation of the traffic control operator, and thus cause the main line signals to be put to stop, even though the lock handle can be operated only part way, because the release of the lock is not permitted by the traffic control operator at that time. The system, according to the present invention, however, obviates this possibility by a stick circuit switch and lock repeater relay which governs the control circuits of main line signals governing traffic through the track switch. This relay cannot be released to put the signals controlled thereby to stop until the remotely controlled energization of the electric lock for the track switch by a traffic control operator. The present invention, however, still retains the feature of the switch repeater relay checking, in its pickup circuit, restoration to the normal conditions of the switch lock mechanism.

An object of the present invention, therefore, is to provide circuit means for putting main line signals governing passage through a locked hand throw switch to stop only after supervisory release of the lock, as compared to the putting of these signals to stop in response to the sole attempt of a trainman to release the lock.

Another object of the present invention is to check restoration to normal conditions of the mechanism of an electric lock in the pickup circuit of a switch and lock repeater relay, but maintain the switch repeater

2

relay picked up until release of the lock by the supervisory control of a traffic control operator, irrespective of any sole attempt by a trainman to release the lock.

Other objects, purposes, and characteristic features of the present invention will be in part obvious from the accompanying drawing and in part pointed out as the description of the invention progresses.

In describing the invention in detail, reference is made to the accompanying drawing in which similar letter reference characters are used to designate parts having similar functions, and in which the circuit organization illustrated is for the control of an electric lock and signals associated with an outlying track switch.

The accompanying drawing illustrating the present invention in a schematic manner is more particularly organized for simplicity in the disclosure of the principles and mode of operation of the present invention, rather than to attempt to disclose the specific construction and arrangement of parts which may be desirable in the practice of the invention. Thus symbols are employed in the conventional manner for the various devices and sources of electric current. The symbols (+) and (—) are used to indicate the connections to the positive and negative terminals respectively of suitable batteries or other sources of direct current.

Although the present invention is illustrated in the drawing as being applied to a main stretch of single track having signals for governing traffic in both directions, it is to be understood that the invention can be readily applied to a supervisory controlled electric lock for practically any outlying hand operated track switch for either single or double track. The main stretch of track illustrated is divided into track sections in the usual manner, and two double intermediate automatic signal locations are illustrated wherein signals 2 and 4 govern eastbound traffic (to the right) and signals 3 and 5 govern westbound traffic (to the left). Signal 2 governs traffic through track sections 2T, RT, and 5T respectively for eastbound traffic, an outlying switch W being provided for tying a spur track to the main line track in the track section 5T.

The switch W has associated therewith an electric switch lock mechanism, which may be of any suitable type, such as is disclosed, for example, in the Stephenson patent, No. 1,710,668, dated April 23, 1929. In this type of switch lock, a lock rod 10 is connected to the switch points and is retained in a normal position by a lock plunger 11, locking the switch points in such normal position. The switch points cannot be moved to the reverse position (in a direction indicated by the arrow associated with the lock rod 10) until the lock plunger 11 has been raised by a lock handle LH. This lock handle LH can be moved a limited amount, opening certain normally closed contacts, and closing certain normally open contacts (not shown), as required for different circuits to be controlled; but the operation of the lock handle LH is limited by the locking dog 39 which prevents the release of the lock rod 10 until the electric lock winding WL is energized to move the locking dog 39 to a non-engaging position. When the locking dog 39 is lifted by the energization of the winding WL, the lock handle LH can be moved in a counterclockwise direction to raise the lock plunger 11 to disengage the lock plunger from the hole in the lock rod 10, and permit hand operation of the track switch to its reverse position. It will be noted that the lock handle LH cannot be returned to its normal position until the track switch W has been returned to its normal position in alignment for main line traffic because, with the lock rod 10 in a reverse position, there is no hole through which the lock plunger 11 may pass.

Also associated with the switch W is a suitable switch circuit controlled SCC having contacts which are closed only when the switch is in a full normal position.

Although the signals are illustrated as being of the conventional searchlight type, other types of signals commonly employed in practice could as well be used.

The track sections 2T, RT, and 5T have track relays 2TR, RTR, and 5TR respectively associated therewith in the usual manner.

A relay WLZ is provided at the outlying track switch W, subject to remote control by direct wire, or by code communication in a centralized traffic control system, according to the requirements of practice. A suitable switch lock control lever WLL is illustrated as a manual control lever subject to operation by a traffic control operator at a point remote from the outlying track switch W, such as at a central office.

A switch and lock repeater stick relay WLPS is provided at the location of the outlying switch as a repeater of the normal conditions of the switch lock and the switch points of the outlying switch W.

The control circuits are illustrated for the opposing signals 2 and 5 as being of the conventional APB type as shown for example in the Patent No. 2,125,243, dated July 26, 1938, in order to illustrate how these signals are governed by the switch lock for the outlying track switch W.

Yellow-green signal repeater relays 3YGP and 4YGP are provided in the usual manner at the respective signal locations for governing the polarity of energization of the signal control circuits for the signals 5 and 2 respectively.

Inasmuch as the signalling system illustrated is for a single track APB system, a conventional directional stick relay S is provided at each signal location for governing energization of the line circuit extending to the next signal in the rear for use in governing signal indications for following trains.

In addition to the conventional signal control line circuit, east and west traffic direction relays EF and WF are provided at the location of the outlying switch W for use in governing the control of the locking of such switch.

Having thus described the general organization of the system according to the present invention, more detail consideration of the organization will be given upon consideration of the mode of operation of the system under typical operating conditions.

Operation

Normally, with the trackway unoccupied by trains and with the outlying track switch W in its normal position and locked, the switch and lock repeater relay WLPS is in its energized position, permitting the clearing of the opposing signals 2 and 5 according to conventional signalling practice.

The stick circuit by which the relay WLPS is normally energized includes back contact 19 of relay WLZ, normally closed contact 20 of the switch circuit controller SCC, front contact 21 of relay WLPS, back contact 22 of the switch lock control armature, normal contact 23 of the switch circuit controller SCC, and the winding of relay WLPS. The pickup circuit for the relay WLPS is normally closed, but is shunted in part by the stick contact 21 in the circuit just described. This pickup circuit for relay WLPS extends from (+), including back contact 19 of relay WLZ, normally closed contact 20 of the switch circuit controller SCC, normally closed contact 24 of the door operated contact mechanism of the switch lock, rotary circuit controller contact 25 of the switch lock which is closed only with the switch lock handle in its normal position as shown, contact 22 of the armature of the switch lock when in its deenergized position, normally closed contact 23 of the switch circuit controller SCC and winding of relay WLPS, to (-).

Signal 2 for governing eastbound traffic is normally

energized over its line circuit in accordance with the signal 4 being clear. The circuit for the energization of the winding of signal 2 extends from (+), including front contact 26 of relay 4YGP, front contact 27 of relay 5TR, front contact 28 of relay WLPS, front contact 29 of relay RTR, front contact 30 of relay 2TR, winding of signal 2 and front contact 31 of relay 4YGP, to (-).

Signal 5 is similarly normally energized by a line circuit extending from (+), including front contact 32 of relay 3YGP, front contact 33 of relay 2TR, front contact 34 of relay RTR, front contact 35 of relay WLPS, front contact 36 of relay 5TR, winding of signal 5 and front contact 37 of relay 3YGP, to (-).

Front contact 45 of relay 3S is to apply energy to the line circuit for westbound traffic following trains when a train has just passed signal 3. Front contact 46 of relay 4S serves a similar purpose for the opposite direction of traffic.

For considering a first typical condition for the release of the locking of outlying track switch W, it will be assumed that an eastbound train is proceeding along the main track and comes to a stop in the release track section RT in direct approach of the outlying track switch W. Under these conditions, the signals 2 and 5 are both at stop by reason of their signal control circuits being opened by the front contacts 29 and 34 of the release track relay RTR.

The usual procedure is for the trainman to phone into the centralized traffic control office and ask the operator of the centralized traffic control machine for the release of the locking for the track switch W. The trainman then opens the door of the switch lock mechanism case, and the electromagnetically operated latch of the locking mechanism will then become actuated upon the operation by the traffic control operator of the control switch WLL to its right-hand position. Such operation on the part of the operator at the remote control point causes the picking up of the relay WLZ by the energization of an obvious circuit including the contact 38 of the door operated switch circuit controller (closed only when the door is open).

With the track section RT occupied by the train, with the door of the lock mechanism open, and with permission for release of the lock having been designated by the operator of the traffic control machine at a remote point, the winding WL of the electric lock becomes energized so as to lift the latch 39 and permit the rotation in a counterclockwise direction of the lock handle LH to raise the plunger 11 and disengage the locking for the track switch W. The circuit by which the winding WL of the lock mechanism is energized at this time extends from (+), including back contact 40 of relay RTR, front contact 41 of relay WLZ, contact 42 of the door operated circuit controller (closed only when the door is open) and winding WL of the lock mechanism, to (-).

With the picking up of the locking dog 39, the lever LH can be fully rotated in a counterclockwise direction to withdraw the lock plunger 11 from the lock rod 10 and thus permit the hand operation of the track switch W to its reverse position.

After the train has proceeded into the spur track over the track switch W, the track switch is then restored to its normal position, and the lever LH is rotated clockwise to the normal position in which it is illustrated, thus causing the plunger 11 to be restored to a locking position with respect to the switch lock rod 10.

Upon restoration of the lever LH to its normal position, the above described pickup circuit for the relay WLPS is closed, and relay WLPS becomes picked up. Upon the picking up of this relay, the signal control circuits become closed for signals 2 and 5 by reason of the closure of front contacts 28 and 35 respectively of relay WLPS, thus completing restoration to normal conditions of the switch lock and signal control organization after passage of a train as has been described.

The condition will now be considered where the release of the lock for the outlying switch W is desired upon movement of a train off of the spur track and into the main track. Under these conditions, a trainman phones into the office of the centralized traffic control operator for permission to move out into the main track, and then proceeds as before by opening the door of the switch lock mechanism and rotating the handle LH in a clockwise direction to raise the lock plunger 11 from its position of engagement with the switch lock rod 10.

It will be noted that the above described pickup circuit for the switch and lock repeater relay WLPS is opened upon the opening of the door of the lock mechanism by the opening of contact 24, and upon initial movement of the lever LH by the opening of contact 25 of the rotary switch circuit controller. The relay WLPS, however, remains picked up until action has been taken on the part of the traffic control operator to permit the energization of the winding WL of the electric lock. In other words, because of the stick circuit for relay WLPS including back contact 19 of relay WLZ, normally closed contact 20 of the switch circuit controller SCC, front contact 21 and back contact 22 of the armature of the electromagnet WL, and normally closed contact 23 of circuit controller SCC, the relay WLPS is not dropped away to put signals on the main track to stop until supervisory control for the release from the locking position of the electric lock is received. In this way, a trainman is prevented from causing the signals of the main track to be put to stop before he has received permission by supervisory control for the release of the locking for the track switch W.

Upon receiving supervisory control in the form of picking up energy for the relay WLZ, the winding WL of the switch lock becomes energized provided that the traffic direction relays EF and WF are both picked up to indicate that there is no train in the immediate vicinity proceeding in either direction. These relays are picked up provided the signal control circuit for their respective directions are energized, thus indicating that there is no train present between the opposing signals 2 and 5. With these relays picked up, the winding WL of the switch lock mechanism can become energized upon the picking up of relay WLZ. The circuit for the energization of winding WL of the switch lock extends from (+), including front contact 43 of relay EF, front contact 44 of relay WF, front contact 41 of relay WLZ, contact 42 of the door operated contact, and winding WL of the switch lock, to (-).

Upon the energization of the winding WL of the switch lock, the switch lock armature is attracted so as to actuate the locking dog 39 to its disengaging position and open back contact 22 in the stick circuit for the relay WLPS. Relay WLPS has, however, had its stick circuit deenergized just prior to this time by the opening of back contact 19 of relay WLZ. Thus, relay WLPS becomes dropped away, and the dropping away of this relay opens the circuits for the signals 2 and 5 governing passage through the track switch W by the opening of contacts 28 and 35 respectively.

Full counterclockwise operation of the lock handle LH is now permitted, and the lock plunger 11 can be thus disengaged from the hole in the lock rod 10 so as to permit the hand operation of the track switch.

When the track switch W is restored to its normal position after passage of the train into the main track, the relay WLPS is again picked up by the energization of its pickup circuit as has been described, and the picking up of this relay completes restoration of the system to normal.

Having thus described one specific embodiment of the present invention as applied to the control of an outlying track switch associated with a main stretch of single track, it is desired to be understood that this form of the invention has been presented more particularly to facilitate the disclosure of the present invention as to the principles and mode of operation involved, rather than to limit the present invention to the specific form shown; and it is

to be further understood that various modifications, adaptations, and alterations may be applied to the specific form shown in accordance with the requirements of practice, except as limited by the appending claims.

5 What I claim is:

1. In a signal control system having a signal governing traffic through a hand throw switch, an electric lock mechanism connected to said hand operated track switch, said electric lock mechanism having a lock plunger operable between a full normal locking position and a releasing position by manually operable lock control handle, said electric lock having an electromagnet operating a locking dog and effective when the electromagnet is deenergized to permit only limited movement of said lock control handle away from said full normal position, a lock circuit controller operated by said lock control handle having a normal contact closed only when said handle is in said full normal position, a switch circuit controller connected to said track switch having a normal contact closed only when the switch points are in their full normal positions, a switch and lock repeater relay, a pickup circuit for said switch and lock repeater relay including in series said normal contact of said lock circuit controller and said normal contact of said switch circuit controller, stick circuit means for maintaining said switch and lock repeater relay energized, said stick circuit means being effective to maintain said switch and lock repeater relay picked up irrespective of said normal contact of said lock circuit controller, and said stick circuit means being subject to deenergization upon the energization of said electromagnet, and signal control means for governing said signal including contacts of said switch and lock repeater relay.

2. In a signal control system having a signal governing traffic through a hand throw switch, an electric lock mechanism connected to said hand throw track switch, said electric lock mechanism having a lock plunger operable between a full normal locking position and a releasing position by a manually operable lock control handle,

35 said electric lock mechanism having an electromagnet operating a locking dog effective when the electromagnet is deenergized to permit only limited movement of said lock control handle away from said full normal position, a lock circuit controller operated by said lock control handle having a normal contact closed only when said handle is in said full normal position, a door contactor operated by the door of said mechanism having a normally closed contact opened by the opening of the door, a switch circuit controller connected to the track switch and having a normal contact closed only when the track switch

50 is in its full normal position, a switch and lock repeater relay, a pickup circuit for said switch and lock repeater relay including said normally closed contact of said door contactor and said normal contact of said lock circuit controller and said normal contact of said switch circuit controller, stick circuit means for maintaining said switch and lock repeater energized, said stick circuit means being effective to maintain said switch and lock repeater relay picked up irrespective of said normal contact of said lock circuit controller and said normally closed contact

55 of said door circuit controller, said stick circuit means being subject to deenergization upon the energization of said electromagnet, and signal control means for governing said signal including a contact of said switch and lock repeater relay.

60 65 3. In a signal control system having an electric lock mechanism mechanically connected to a hand operated track switch, said electric lock mechanism having a lock plunger operable between a full normal locking position and a releasing position by a manually operable lock control handle, said electric lock mechanism having an electromagnet operating a locking dog effective when the electromagnet is deenergized to permit only limited movement of said lock control handle away from said full normal position, a lock circuit controller operated by said

70 75 lock control handle having a normal contact closed only

when said handle is in its full normal position, a switch and lock repeater relay, a switch circuit controller connected to said track switch having a normal contact closed only when the switch points are in their full normal positions, a pickup circuit for said switch and lock repeater relay including said normal contact of said lock circuit controller and said normal contact of said switch circuit controller, and stick circuit means for maintaining said switch and lock repeater relay energized, said stick circuit means being effective to maintain said switch and lock 10

repeater relay picked up irrespective of the opening of said normal contact of said lock circuit controller, and said stick circuit means being subject to deenergization upon the energization of said electromagnet.
